(57) **CLAIM**

The ornamental design for a valve body, as shown and described.

DESCRIPTION

FIG. 1 is a perspective view of a valve body showing my new design;

FIG. 2 is a top plan view thereof;

FIG. 3 is a front elevational view thereof;

FIG. 4 is a rear view thereof;

FIG. 5 is a bottom view thereof;

FIG. 6 is a right side view thereof; and,

FIG. 7 is a left side view thereof.

The broken line showing of unclaimed portions of the valve body form no part of the claimed design.
